UNITED STATES PATENT OFFICE.

MICHAEL P. MURRAY, OF CRESSON, PENNSYLVANIA.

RAILROAD CLAMP.

1,045,730.

Specification of Letters Patent. Patented Nov. 26, 1912.

Application filed February 14, 1911. Serial No. 608,539.

To all whom it may concern:

Be it known that I, MICHAEL P. MURRAY, a citizen of the United States, residing at Cresson, in the county of Cambria and State of Pennsylvania, have invented new and useful Improvements in Railroad-Clamps, of which the following is a specification.

This invention relates to railway tie plates and consists in the peculiar construction, arrangement and combination of parts which will be hereinafter fully set forth and claimed.

The object of the invention is to provide a tie plate for railway rails which is extremely simple in construction, which can be manufactured at a comparatively low cost, and which will perform the functions for which it is intended with ease and accuracy.

In the accompanying drawings, Figure 1 is a perspective view of a tie plate constructed in accordance with the present invention, the same being shown attached to the tie and a rail being indicated by the dotted lines. Fig. 2 is a central longitudinal sectional view of the tie plate. Fig. 3 is a perspective view of one of the members comprising the plate. Fig. 4 is a similar view of the co-acting member. Fig. 5 is a sectional view of a modified form of the device.

As illustrated, and as preferred, my tie plate comprises two main parts or members designated by the numerals 1 and 2. Both of these members 1 and 2 are of a substantially rectangular form. The member 1 is provided on its upper surface and at one end thereof with a centrally located enlargement 3 having an upwardly and inwardly projecting rail flange engaging member 7. This enlargement extends inwardly a short distance. The tie plate 1 is centrally cut away from the inner wall 4 of the enlargement to its opposite edge, thus forming a longitudinal opening 4^a. Each side wall of the opening 4^a lies in the plane of the corresponding side face of the enlargement 3 and the overlying rail flange engaging member 7.

The overlying member 7 forms, with the upper surface of the enlargement 3, a pocket 7^a for the reception of the rail flange. The enlargement 3 is provided with a vertically disposed rectangular opening 13 positioned outwardly with respect to the pocket 7^a and adapted to receive a tie retaining spike. The member 1 is also provided at each side of the enlargement 3 with a rectangular vertical spike opening 6 and is further provided

adjacent its other extremity with similar spike openings 5 positioned on each side of the longitudinal opening 4^a. The member 2 is of similar area to the member 1 and is centrally provided on its under surface adjacent one end with a longitudinally extending enlargement 12. This enlargement is of a width equal to the width of the longitudinal cut-away portion or opening 4^a in the member 1. The member 2 is provided on its upper surface and at the same end with an upwardly and inwardly projecting rail flange engaging member 9, which is positioned directly above the enlargement 12 and has each of its side faces lying in the plane of the corresponding longitudinal faces of the enlargement 12. The enlargement 12 extends inwardly from the end of the member 2 to a point 10^a, from which point the member 2 is centrally cut-away to its opposite edge, thus forming a longitudinal opening 11. The flange engaging member 9 forms, with the upper surface of the member 2, a pocket 10 similar to the corresponding pocket 7^a on the member 1. Each side wall of the longitudinal opening 11 lies in the plane of the corresponding side faces of the member 9 and enlargement 12, and is therefore equal in width to the opening 4^a in the member 1. The enlargement 12 in the member 2 is provided with a vertical rectangular spike receiving opening 14 which extends upwardly through the member 9 but is positioned outwardly with respect to the pocket 10. The member 2 is provided at each side of the member 9 where it joins the same with a vertical rectangular spike opening 15. Similar spike openings 15^a are provided adjacent the opposite end of the member 2 at each side of the opening 11.

When the members 1 and 2 are assembled in rail engaging position the enlargement 12 of the member 2 fits into the opening 4^a of the member 1, so that its outer face is flush with the outer face of the extremity of the member 1, and the side walls of the cut-away portion in the opposite end of this member 2 engage the sides of the enlargement 3 on the member 1. The thickness of the member 2 at the enlargement 12, is equal to the height of the enlargement 3 on the member 1, so that when these members are assembled the upper surface of said enlargement 3 will lie in the plane of the upper surface of the member 2.

these surfaces form a united bearing surface for the base of the rail. In this position of the two members the overlying members 7 and 9 project inwardly toward each other so as to engage the upper surfaces of the rail flanges, and the spike receiving openings 15 in the member 2 are in alignment with the similar openings 5 in the member 1. The spike openings 15^a in the member 2 are also in alignment with the openings 6 in the member 1. When the two members are assembled in this manner, as shown in Fig. 1, with a rail base resting on their upper surfaces and having its flanges received by the pockets 7^a and 10 of the two members, and spikes are driven through their respective openings into a supporting tie, the joint thus formed is very compact and strong.

In Fig. 5 I have illustrated a slightly modified form of the device. In this figure the clamping means comprises a pair of members 17 and 18, each of these members being constructed of a single sheet of material. The member 17 is bent inwardly upon itself to form an overlying portion 19, and the member 18 is similarly bent upon itself to form an overlying portion 20. The overlying portion 20 of the member 18 is flattened upon the said plate for a short distance and then extends upwardly at an angle to form the rail flange engaging member 22. The overlying portion 19 of the member 17 is flattened for a short distance and then extends upwardly at an angle to form the rail flange engaging member 21. When the member 18 is placed upon the member 17 and its end is slid into the enlarged angle or pocket of the member 17 the rail flange engaging members are in operative position. The member 17 is provided with a spike receiving opening which extends upwardly through its flattened overlying portion 19 and is also provided adjacent its opposite extremity with a similar spike opening. The member 18 is provided with a spike opening which extends upwardly through the flattened overlying portion 20 and is adapted to register with the opening in the end of the member 17 when the two members are assembled.

From the above description, taken in con-

nection with the accompanying drawings, it will be noted that I have provided an extremely simple and thoroughly effective device for the purpose intended, and while I have illustrated and described the preferred embodiment of the improvement, as it now appears to me, minor changes in the details of construction within the scope of the following claim may be resorted to if desired.

Having thus fully described the invention, what I claim as new is:—

A rail clamp comprising a substantially rectangular plate provided on its upper surface and at one extremity with a central enlargement, said plate being provided with a longitudinal slot extending from the inner face of said enlargement to the opposite extremity of the plate and being equal in width to said enlargement, an inwardly extending engaging member formed on said enlargement and overlying the same, said plate being provided with a vertical spike opening extending through its engaging member and enlargement, said plate being further provided with a vertical spike opening adjacent each corner thereof, a second superimposed plate provided on its under surface and at one end thereof with a depending central enlargement adapted to be slidably received by the slot in the first plate, said second plate being formed with a longitudinal slot extending from the inner edge of said enlargement to the opposite end thereof and adapted to receive slidably the enlargement on the first plate, and an inwardly extending engaging member formed on said second plate above the depending enlargement and overlying the said slot, said second plate being provided with a vertical spike opening extending through its enlargement and engaging member, and further provided adjacent each corner with a spike opening adapted to align with the corresponding spike openings in the first plate when assembled.

In testimony whereof I affix my signature in presence of two witnesses.

MICHAEL P. MURRAY.
